ELI L. SEGER AND SAMUEL L. SMITH, OF YONKERS, NEW YORK.

Letters Patent No. 68,533, dated September 3, 1867.

IMPROVED CLAMP FOR HINGES.

The Schedule referred to in these Letters Patent and making part of the same.

TO ALL WHOM IT MAY CONCERN:

Be it known that we, ELI L. SEGER and SAMUEL L. SMITH, of Yonkers, in the county of Westchester, and State of New York, have invented a new and improved Clamp for Hinges; and we do hereby declare that the following is a full, clear, and exact description thereof, which will enable others skilled in the art to make and use the same, reference being had to the accompanying drawings, forming part of this specification.

The present invention relates to a clamp for butt hinges more particularly, which clamp is so constructed that it can be placed over the leaves of a hinge when closed, and so operated as to firmly and tightly hold and bind them together, thus preventing their being opened one from the other until the clamp is released. In the accompanying plate of drawings our improved clamp is illustrated—

Figure 1 being a face view of the same with it applied to the butt of a hinge, shown in red lines, and

Figure 2 a transverse horizontal section taken in the plane of the line x x , fig. 1.

Similar letters of reference indicate like parts.

A, in the drawings, represents our improved clamp, which consists of a frame, B, cut out in and along its centre suitably to fit over and upon the two leaves of a hinge when closed the one upon the other. C, a cam hung to the frame B, upon one side of the slot or opening D, which cam is provided with a handle-lever, E, suitable for turning it, and is so-formed as to bear against and thus to bind and to hold the two leaves of a hinge together when closed the one upon the other, and the clamp is applied thereto at the butt.

By means of a clamp of the form above described it is plainly obvious that the hinge or hinges to a door, when the door is closed, can be securely and tightly bound together, and in a most simple, cheap, efficient, and suitable manner.

Having thus described our invention, we claim as new, and desire to secure by Letters Patent—

A clamp for hinges, etc., consisting of frame A and eccentric or cam C, substantially as and for the purpose described.

ELI L. SEGER,
SAMUEL L. SMITH.
